CLAIM

The ornamental design for an e-book page turning accessory, as shown and described.

DESCRIPTION

FIG. 1 is an isometric top view of an e-book page turning accessory showing my new design;

FIG. 2 is a front view thereof, showing the cord and the clip in an alternate position for use;

FIG. 3 is a rear view thereof;

FIG. 4 is a top view thereof;

FIG. 5 is a bottom view thereof;

FIG. 6 is a right view thereof; and,

FIG. 7 is a left view thereof.

The cord seen in FIGS. 1-7 is shown with a symbolic break in its length. The appearance of any portion of the article in between the broken lines, including the symbolic break lines themselves, forms no part of the claimed design.
